BED LIFT

James O. Chambers, Fort Worth, Tex.

Application May 18, 1943, Serial No. 487,503

12 Claims. (Cl. 5—83)

The present invention relates to bed lifts, and more particularly to simple, efficient, and comfortable means for raising a patient.

An important feature of the invention consists in providing a bed lift with a transversely disposed flexible member for supporting the patient, and operatively connecting the supporting member to means which automatically tightens the supporting member as the latter is raised to lift the patient from the bed.

Another object consists in providing a lift attachment which can be readily connected to various types and sizes of beds at a minimum expenditure of time and effort, and in which the parts are arranged and constructed to permit the attendants to care for the patient without being handicapped or obstructed in their work.

Other objects and advantages of the invention will become apparent from the following description, when taken in conjunction with the accompanying claims and drawings.

Referring to the drawings, which show a preferred embodiment of the invention:

Figure 1 is a perspective view of a hospital bed showing my improved lift associated therewith;

Figure 2 is a transverse sectional view taken substantially along the line 2—2 of Figure 1 and showing parts in dotted lines in their raised positions;

Figure 3 is a detail sectional view with parts broken away for clearness of illustration;

Figure 4 is a sectional view taken substantially along the line 4—4 of Figure 3;

Figure 5 is a sectional view taken substantially along the line 5—5 of Figure 4;

Figure 6 is a detail sectional view of one of the supporting cross-pieces taken along the line 6—6 of Figure 3;

Figure 7 is a detail perspective view of the operating shaft;

Figure 8 is a detail view of one end of the operating shaft, showing in dotted lines the different positions which may be assumed by the operating handle; and

Figure 9 is a sectional view taken substantially along the line 9—9 of Figure 8.

Referring to the drawings, in which like numerals indicate like parts in the several views, 18 designates a hospital bed having the side rails 11 and end rails 12 to which are secured the springs 13, so as to provide a support for the mattress 14.

Associated with the bed are a pair of casings or gear boxes 15 and 15', each of which is pro-

vided with an upwardly diverging housing 16 that terminates at its lower end in an enlarged annular shoulder 17 which, in turn, is formed with a flange or web 18 connected to the inner wall of the casing.

A tubular member or sleeve 19 extends into each of the housings 16 and is revolvably mounted therein by the ball bearings 20 at the upper end of the housing and the ball bearings 21 carried by the lower end portion of the tubular member. The tubular member 19 is interiorly threaded as at 22, and these threads mesh with the external threads 23 on a worm or threaded drive shaft 24 so that rotation of the shaft 24 imparts axial or longitudinal movement to the tubular member 19. The lower end of the worm 24 has a smooth portion 25 which extends through the flange 18 and has associated therewith the ball bearings 21'. A beveled gear 26 is non-rotatably secured as at 27 to the shaft 24. Gear 26 meshes with a complementary beveled gear 28 having a hub 29 journaled in the ball bearings 30 mounted in a tubular boss 31 that extends inwardly from the lower end of each of the casings 15 and 15'.

A cross-piece 32 formed with a trough 33 in its upper surface (Figure 3) is provided with a depending arm 24' which extends a limited distance within the upper end of the adjacent tubular member 19 of the casing 15 and is welded or otherwise secured thereto so that the tubular member 19 and the cross-piece 32 constitute an integral structure that is raised or lowered upon the rotation of the shaft 24. The trough 33 is positioned to receive one end of a flexible or extensible supporting member which may be made of any suitable strong and durable fabricated material, such as canvas or the like. As shown, this supporting member comprises two spaced straps or bands 34 and 35 which have their end portions 36 extending into the trough 33. A bar 37 extends the length of the cross-piece 32 and is arranged to fit within the trough 33 and bear against the end portions 36 of the straps. Clamping means in the form of an eccentric 38 is positioned adjacent each end of the cross-piece 32 and above the bar 37 (Figure 1) and may be secured to the cross-piece in any suitable manner, such as by the ring or strap 39. The eccentric 38 has a handle 40 and is arranged to bear against the bar 37 so as to firmly clamp the end portions 36 of the straps between the wall of the trough and the bar 37. In order to further insure the straps being held in firm engagement, the bar 37 may be provided with teeth 41 which

bear against the straps when the parts are set up.

The opposite end portions 42 of the straps 34 and 35 fit into a trough 43 (Figure 6) formed in a cross-piece 44 which extends substantially parallel to the cross-piece 32. A bar 45 similar to the bar 37 fits within the trough 43 so as to bear against the end portions 42 of the straps. An eccentric 46 is mounted adjacent each end of the cross-piece 44 and is secured thereto by a fastening ring 47. The eccentric 46 has a handle 48 arranged to move the eccentric into and out of clamping engagement with the adjacent end portions of the straps. The cross-piece 44 medially thereof is provided with a depending lug 49 having a threaded opening 50 which receives the threaded portion 51 of a horizontal rod 52 that extends through a tubular member 53. The member 53 has a depending arm 24a which extends into the upper end of the adjacent tubular member 19 and is welded or otherwise secured thereto in the same manner as the arm 24'. The outer end portion of the rod 52 has a laterally disposed arm or portion 53' to which is connected a handle 54. It will be seen that upon the rotation of the shaft 52 by the manual actuation of the handle 54, that the straps 34 and 35 may be maintained taut or be loosened according to the desired comforts of the patient. Moreover, the driving means carried by the casings 15 and 15' constitute vertically inclined operating means which are axially movable relative to the casings and are connected to the ends of the transverse flexible or extensible supporting means to insure the tubular members 19 and their associated parts, when elevated, being moved away from each other, so as to tighten the supporting means.

An operating shaft 55 extends through horizontally aligned openings 56 in the casings 15 and 15' and is provided with spaced slots or grooves 57 and 58 which slidably receive keys 59 on the beveled gears 28 so as to rotatably connect these gears to the shaft 55. One end of the shaft 55 has a reduced threaded portion 60 (Figure 3) which extends beyond the outer wall of the casing 15, so as to receive a winged nut 61. The other end portion of the shaft 55 is bent laterally as at 62 and carries a handle 63. It will be seen that the shaft 55 may be readily attached to the casings 15 and 15' to operate the gears, and that when the parts are set up, the wing nut 61 will firmly bear against the adjacent wall of the casing 15, to maintain the lift in a firm position. Each of the casings 15 and 15' is formed on its inner side with spaced flanges 64 which are substantially the same width as the side rails 11, so as to provide channel bars which engage the rails in the manner as shown in Figure 3. Clamping screws 65 may be associated with the lower flanges 64 in order to coact with the clamping means 61 to insure the casings 15 and 15' and their associated parts being firmly held in position on the bed. While the lift has been shown in the form of an attachment which may readily be detachably connected to a hospital or any other type of bed, it will be manifest that it may be also installed as a permanent part of a bed structure. Instead of the gear mechanism, hydraulic or pneumatic means may be used for operating the tubular members 19 or other movable means connected to the flexible supporting members for raising and lowering the latter.

In order that the operating handles 54 and

63 may assume an out of the way position when not in use, means are provided for allowing these handles to fall to a vertical position. This may be effected by providing the handle 63 (Figure 7) with a flat reduced inner end portion 66 which extends into a vertical slot 67 in the arm 62, so as to be movable therein. The reduced end portion 66 has laterally projecting flat lugs 68 (Figure 9) which slidably fit in straight slots 69 that communicate with curved slots 70 formed in the sides of the arm 62 opposite the recess 67. Thus it will be seen that when the handle 63 is in its horizontal position, the lug 68 snugly fits in the straight slots 69 so as to rotate the shaft 55 upon the actuation of the handle. When the handle 63 is moved upwardly into the recess 67, the lug 68 rotatably fits within the curved slot 70, so as to allow the handle 63 to be moved independently of the arm 62 and thus fall to an out of the way vertical position, so as not to interfere with the attendant when treating the patient. The reduced end of the handle 54 is similarly provided with flat outwardly projecting lugs 71 arranged to be slidable in a keyhole slot 72, so as to either assume a horizontal position as shown in Figure 3 or to extend downwardly in alignment with the arm 53 of the shaft 52.

In operation, assuming that the lift attachment is of the type arranged to be detachably connected to the bed, the casings 15 and 15' are connected to the side rails 11 through the flanges or channel members 64 at a point adjacent the body of the patient. The shaft 55 which is normally carried by the casing 15' now extends under the bed and is passed through the openings 56 in the casing 15 and locked to the beveled gear therein through engagement of the key 59 with the groove 58. The thumb nut 61 is then applied to the threaded end 60 to firmly maintain the casings in rigid position on the bed. If desired, the clamping screws 65 may be used to insure the lift attachment being maintained in a fixed position. The straps 34 and 35 are positioned under the body of the patient and connected to the cross-pieces 32 and 44 by the rods 37 and 45 and their associated clamping levers. The handle 63 is then rotated, which causes the tubular members 19 and their associated parts to be simultaneously elevated and moved away from each other, thus raising the patient from the bed and at the same time further separating the cross-pieces 32 and 43 from each other so as to gradually tighten the straps 34 and 35. When the body of the patient is lifted the proper distance away from the bed or mattress, a bed pan or the like may be positioned under the patient, thus providing simple and efficient means for comfortably and conveniently lifting the patient. The spaced bearings 20 and 21 rotatably support the tubular members 19 in the housings 16, thus providing means to permit free turning movement of the members 19 and their associated parts, so that when the weight of a patient is applied to the flexible supporting means or straps 34, there is no tendency for these parts to bind as would be the case if the tubular members were fixed or non-rotatable. In other words, the flexible members are connected to the inclined supporting means so that the patient may twist or turn without physical discomfiture. As the lubricated parts are enclosed within the casings there is no danger of oil or grease soil-

ing the clothes of the attendant or patient. It will also be seen that the attachment may be used to raise the patient so that X-ray pictures may be taken, or to raise a patient in a cast or splint, or when some operating procedure inhibits the patient from lying comfortably on his back. Due to the simplicity and compactness of the parts, the attendant may easily operate the lift from one side of the bed, and, if necessary, may also handle the patient without difficulty.

The straps 34 and 35 are so spaced apart that when a bed pan is to be used, an additional movable seat can be supported by the straps so that the patient may sit in a comfortable position. As the tubular members 19 and their associated parts diverge upwardly from each other, it will be seen that the straps 34 and 35 are gradually tightened, due to the increased distance between the crosspieces 32 and 45 as the rods are elevated, thus eliminating the necessity of manually tightening the flexible support during this operation. Should it be necessary, for any reason, to either further tighten or loosen the straps 34 and 35, this may be done by actuating the handle 54 on the rod 52. When the patient is lifted the proper distance, the handles 54 and 63 are moved to their inoperative vertical positions, so as not to interfere with the attendant handling the patient. As the straps are readily removable, it will be seen that should they become soiled, they can be quickly changed for clean straps, thus insuring the provision of sanitary means for lifting the patient.

While the flexible supporting member has been shown in the form of straps, it will be manifest that other similar means may be used, such as a single piece of canvas having an opening in the center and the opening arranged to receive rubber rings attached to the canvas. In incontinent cases, the flexible supporting means may be in the form of plastic, oil silk, or similar material.

The lift may be readily dismantled by disconnecting the straps from their supports and removing the nut 61 from the shaft 55 which permits the withdrawal of the casing 15 from the bed and the shaft. The casing 15' which carries the shaft 55 may then be removed, and, if necessary, the lift may be attached to another bed for the purpose of raising the patient. The grooves 57 and 58 in the shaft 55 permit the convenient removal of the casing 15 and its associated parts from the shaft without disturbing the connection of the shaft with the casing 15'. The shaft 55 may be provided with a continuous groove, in which event it may be completely withdrawn from the casing 15' as well as the casing 15.

Thus, it will be seen that an automatic or self-tightening lift is provided for comfortably and conveniently raising a patient from a bed and which is so constructed and arranged as to allow the nurse or attendant to properly care for the patient without being bothered by objectionable or protruding parts which might seriously interfere with her work.

While the lift attachment has been shown as separate from the bed, it will be obvious that it could be readily installed as a permanent part of a hospital or other type of bed without in any way interfering with the efficient operation of the device. The threaded engagement of the rods 24 with the revoluble tubular members 19 coact with the meshed gears to maintain the flexible means and its associated parts in any

predetermined adjusted position relative to the bed without requiring the use of additional locking means.

It will be understood that the form of the invention shown is merely illustrative of a preferred embodiment, and that such changes may be made as fall within the purview of one skilled in the art, without departing from the spirit of the invention and the scope of the appended claims.

I claim:

1. In combination with a bed, an invalid lifting device comprising a pair of casings disposed on opposite sides of the bed, inclined lifting means longitudinally movable in said casings, flexible supporting means extending across the bed and connected to the lifting means, and means for imparting movement to the lifting means, the inclined lifting means when raised being moved away from each other to move the opposite ends of the flexible supporting means outwardly to tighten the same.

2. In combination with a bed, an invalid lifting device comprising a pair of casings disposed on opposite sides of the bed, inclined lifting means longitudinally movable in said casings, bearing means on said casing rotatably mounting said lifting means thereon, flexible supporting means extending across the bed and connected to the lifting means, and means for imparting movement to the lifting means, the inclined lifting means when raised being moved away from each other to move the opposite ends of the flexible supporting means outwardly to tighten the same, said lifting means being rotatable in the casings to allow free turning movement thereof and prevent binding when the weight of a patient is applied to the flexible supporting means.

3. In combination with a bed, an invalid lifting device comprising a pair of casings disposed on opposite sides of the bed and connected to the side rails thereof, each of said casings having a vertical inclined passage, a tubular member rotatably and axially movable in said passage, drive means operatively connected to the tubular member for imparting axial movement thereto, flexible supporting means extending across the bed and connected to the tubular members, and means for simultaneously rotating the drive means to impart axial movement to the tubular members, the tubular members when raised being moved away from each other so as to tighten the flexible supporting means.

4. In combination with a bed, an invalid lifting device comprising a pair of casings disposed on opposite sides of the bed and connected to the side rails thereof, each of said casings having a vertically inclined internally threaded tubular member axially movable therein, a worm extended into the tubular member and engaging the threads thereof for moving the same, flexible supporting means extending across the bed, means connecting the ends of the supporting means to said tubular members, and means for simultaneously rotating the worms to impart axial movement to the tubular members, said tubular members when raised being moved away from each other so as to tighten the flexible means.

5. In combination with a bed, an invalid lifting device comprising a pair of casings disposed on opposite sides of the bed, inclined operating means axially movable in said casings, exten-

sible supporting means extending across the bed and connected to the operating means, means for imparting axial movement to the operating means in each casing, the inclined operating means when raised being moved away from each other so as to tighten the extensible supporting means, and means carried by one of the operating means and connected to one end of the extensible supporting means for tightening the latter.

6. In combination with a bed, an invalid lifting device comprising a pair of casings disposed on opposite sides of the bed and connected to the side rails thereof, each of said casings having a vertically inclined internally threaded tubular member axially movable therein, a worm extended into the tubular member and engaging the threads thereof for moving the same, flexible supporting means extending across the bed, means connecting the ends of the supporting means to said tubular members, means for simultaneously rotating the worms to impart axial movement to the tubular members, said tubular members when raised being moved away from each other so as to tighten the flexible means, and means carried by one of the tubular members and connected to one end of the flexible means for adjusting the tension of the latter.

7. In combination with a bed, an invalid lifting device comprising a pair of casings disposed on opposite sides of the bed and connected to the side rails thereof, each of said casings having a vertically inclined internally threaded tubular member axially movable therein, a worm extended into the tubular member and engaging the threads thereof for moving the same, flexible supporting means extending across the bed, means connecting the ends of the supporting means to said tubular members, and a gear mechanism connected to each of the worms for imparting axial movement to the tubular members, said tubular members when raised being moved away from each other so as to tighten the flexible means.

8. In combination with a bed, an invalid lifting device comprising a pair of casings disposed on opposite sides of the bed and connected to the side rails thereof, each of said casings having a housing, a vertically inclined interiorly threaded tubular member revolvably mounted in said housing, a worm extending into said tubular member and having an externally threaded portion coacting with the threads on said member, so that upon rotation of the worm axial movement is imparted to said tubular member, flexible supporting means extending across the bed and above the same, means connecting said flexible means to the upper ends of said tubular members, gear mechanism connected to each of the worms, a drive shaft operatively connected to the gear mechanism for simultaneously imparting axial movement to the tubular members to vertically move the flexible means, said tubular members when raised being moved away from each other so as to tighten the flexible means, and means carried by one of said tubular members and connected to one end of the flexible means for adjusting the tension of the latter.

9. In combination with a bed, an invalid lifting device comprising a pair of casings disposed on opposite sides of the bed and connected to the side rails thereof, each of said casings having a housing, a vertically inclined interiorly threaded tubular member axially movable in each housing, a worm extending into said member

and having an externally threaded portion coacting with the threads on said member so that rotation of the worm, imparts axial movement to the tubular member, a cross-piece on the upper end of one of said tubular members, a threaded shaft rotatably mounted on the upper end of the other tubular member, a cross-piece operatively connected to said shaft and disposed substantially parallel to said first-mentioned cross-piece, flexible supporting means extending across the bed and detachably connected to said cross-pieces, means for actuating the threaded shaft for controlling the tension of the flexible means, and driving means operatively connected to the worms for imparting axial movement to the tubular members, said tubular members when moved upwardly being moved away from each other so as to tighten the flexible means.

10. A lift attachment for beds comprising a pair of casings arranged to be secured to opposite sides of a bed, each of said casings having an inclined tubular member axially movable therein, drive means in said tubular member and operatively connected thereto, a cross-piece on the upper end of one of said tubular members, a threaded shaft rotatably mounted on the upper end of the other tubular member, a cross-piece operatively connected to said shaft and disposed substantially parallel to said first-mentioned cross-piece, flexible body supporting means disposed between the cross-pieces, means detachably connecting the ends of the supporting means to said cross-pieces, and means for simultaneously operating the drive means to impart axial movement to the tubular members to move the supporting means vertically, said tubular members in their upward movement being moved away from each other so as to tighten the flexible means.

11. A lift attachment for beds comprising a pair of casings arranged to be secured to opposite sides of a bed, each of said casings having an inclined tubular member revolvably and axially movable therein, an inclined worm extending into the tubular member and operatively connected thereto, a cross-piece on the upper end of one of said tubular members having a trough therein, a threaded shaft rotatably mounted on the upper end of the other tubular member, a cross-piece operatively connected to said shaft and having a trough disposed substantially parallel to said first-mentioned trough, flexible body supporting means disposed between the cross-pieces and having end portions positioned in said troughs, means for clamping the end portions of the flexible means in the troughs, and means for simultaneously rotating the worms to impart axial movement to the tubular members to move the supporting means vertically, said tubular members in their upward movement being moved away from each other so as to tighten the flexible means.

12. A lift attachment for beds comprising a pair of casings arranged to be secured to opposite sides of a bed, each of said casings having an inclined tubular member revolvably and axially movable therein, an inclined worm extending into the tubular member and operatively connected thereto, a cross-piece on the upper end of one of said tubular members having a trough therein, a threaded shaft rotatably mounted on the upper end of the other tubular member, a cross-piece operatively connected to said shaft and having a trough disposed substantially parallel to said first-mentioned trough, flexible body

supporting means disposed between the cross-pieces and having end portions positioned in said troughs, means for clamping the end portions of the flexible means in the troughs, means for simultaneously rotating the worms to impart axial movement to the tubular members to move the supporting means vertically, said tubular mem-

bers in their upward movement being moved away from each other so as to tighten the flexible means, and means carried by one of the tubular members and connected to one end of the flexible means for adjusting the tension of the latter.

JAMES O. CHAMBERS.
